UNITED STATES PATENT OFFICE.

WALTER F. KOKEN AND ANTON J. PICHL, OF ST. LOUIS, MISSOURI.

VALVE MECHANISM FOR INTERNAL-COMBUSTION ENGINES.

1,161,224.

Specification of Letters Patent.

Patented Nov. 23, 1915.

Application filed May 11, 1914. Serial No. 837,652.

To all whom it may concern:

Be it known that we, WALTER F. KOKEN and ANTON J. PICHL, citizens of the United States, residing at the city of St. Louis, State 5 of Missouri, have invented certain new and useful Improvements in Valve Mechanisms for Internal-Combustion Engines, of which the following is a specification.

This invention relates to internal combustion engines of the type in which slide valves are employed for controlling the inlet and exhaust of the gases to and from the cylinders.

One object of our present invention is to 15 provide a multi-cylinder, four-cycle internal combustion engine in which the inlet and exhaust of the gases to and from all of the cylinders is governed by two positively actuated reciprocating valve members arranged in sliding engagement with each other and provided with coöperating openings that align with each other and with the ports in the cylinders so as to establish communication between the cylinders and the inlet and exhaust manifolds of the engine in proper sequence, the coöperating openings in said valve members and the ports in the cylinders being so designed that the pressure in the cylinders is exerted on only a relatively 25 small area of said valve members when the engine is in operation.

Another object is to provide an engine of the construction described in which the valve members are so designed and operated that 35 one cylinder is controlled by a single pair of coöperating openings in said members, the combustion gas passing through said pair of openings into the cylinder when said valve members are in one position and the 40 burnt gases escaping through said openings when said members are in a different position.

Other objects and desirable features of our invention will be hereinafter pointed 45 out.

Figure 1 is a top plan view of an internal combustion engine constructed in accordance with our invention with the cover removed to expose the valve plates; Fig. 2 is a 50 vertical longitudinal sectional view of the engine; Fig. 3 is a top plan view of the engine, looking at a right-angle to the valve members or plates; Fig. 4 is a side elevation of an end portion of the engine showing the valve-operating mechanism, the housing for the latter being shown in section; Fig. 5 is an end elevation of same; Fig. 6 is a transverse sectional view; Figs. 7, 8, and 9 are detailed views of parts of the valve-operating mechanism; Fig. 10 is a top plan view 60 of the upper valve member plate; Fig. 11 is a top plan view of the lower valve plate; Fig. 12 is a top plan view of the cylinder casing; and Fig. 13 is a transverse sectional view of the upper part of the engine, showing a slight modification of our invention. 65

For the purpose of illustration, a four-cycle engine having four cylinders designated by the numerals 1, 2, 3, and 4 is depicted in the drawings, each cylinder having a piston 5 adapted to operate therein in the usual manner. In the head of each cylinder there is provided a relatively narrow port 6 through which the explosive mixture is admitted to and the products of combustion are allowed to discharge from the cylinder at the proper time in the manner hereinafter described. The ports 6 in the heads of the cylinders communicate with a valve chamber or groove 7 which extends longitudinally in the bottom of the cover 8, the latter containing an intake chamber 9 and an exhaust chamber 10, which chambers 9 and 10 preferably extend longitudinally within the cover adjacent to the sides, respectively, thereof and have connections with the intake pipe 11 and exhaust pipe 12, respectively. Passages 13 and 14, which preferably extend transversely within the cover 8 from the chambers 9 and 10, respectively, open into the valve chamber or groove 7, there being as many intake passages 13 and as many exhaust passages 14 as there are cylinders, and the walls of said passages 13 and 14 and the chambers 9 and 10 being 75 arranged to protrude into a water chamber 15 within the cover 8. The top of the cylinder casing is preferably arranged to incline transversely for the purpose hereinafter described, and the sides of the cylinder casing adjacent to the top thereof slope outwardly to form upwardly-diverging flanges 16, the cover 8 being provided at the sides thereof with downwardly-converging flanges 17 which overlap the flanges 16. A 80 key 18, which extends longitudinally between a flange 17 and a flange 16 adjacent thereto, locks the cover 8 upon the top of the cylinder casing, as best seen in Fig. 6, and is itself held in place by a bar or plate 19, which is secured to the flange 16 by bolts 85 20 or other suitable means, and, also the bolts

21 or the like which pass through openings in the flange 17. The water-jacket 22 which surrounds the cylinders is preferably arranged to extend over the tops of same so as to surround the walls of the ports 6, and at one end of the engine the high side of the water-jacket is communicatively connected with the low side of the water chamber 15 in the cover 8 by means of the pipe 23 to allow the water to flow from said water-jacket into said water chamber. At the other end of the engine the water enters the lower part of the water-jacket 22 through a pipe 24 and discharges from the high side of the water chamber 15 through the discharge pipe 25. A spark plug 26 and a priming-valve 27 are provided for each cylinder, the spark plugs being preferably located on one side of the engine and the priming-valves 20 being located on the opposite side.

Communication between the ports 6 in the cylinder heads and the intake passages 13 and the exhaust passages 14 in the cover 8 is established in the proper sequence by means of the plates or valve members 28, which are preferably adapted to reciprocate longitudinally in sliding engagement with each other within the valve chamber or groove 7 in said cover. In the case of a four cylinder engine as illustrated in the drawings, two plates or valve members 28 are preferably employed, the lower plate 28 resting upon the top of the cylinder casing and the upper plate 28 resting upon the lower plate. When the plates 28 are reciprocated in the manner hereinafter described, an opening 29 in the upper plate 28 and an opening 30 in the lower plate 28 establish communication alternately between the port 6 of the cylinder 1 and the intake passage 13 and the exhaust passage 14 above said cylinder at the proper time, an opening 31 in the upper plate 28 and an opening 32 in the lower plate 28 establish communication between the port 6 of the cylinder 2 and the intake passage 13 above the latter at the proper time, an opening 33 in the upper plate 28 and an opening 34 in the lower plate 28 establish communication between the port 6 of the cylinder 2 and the exhaust passage 14 above the latter at the proper time, an opening 35 in the upper plate 28 and an opening 36 in the lower plate 28 establish communication between the port 6 of the cylinder 3 and the exhaust passage 14 above the latter at the proper time, an opening 37 in the upper plate 28 and an opening 38 in the lower plate 28 establish communication between the port 6 of the cylinder 3 and the intake passage 13 above the latter at the proper time, and an opening 39 in the upper plate 28 and an opening 40 in the lower plate 28 establish communication alternately between the port 6 of the cylinder 4 and the intake passage 13 and exhaust passage 14

above the latter at the proper time. In order to strengthen the plates 28 each opening therein may be provided with a partition 28^a or a plurality of such partitions.

The means for actuating the valves of the engine is of novel construction and preferably operated from the crank shaft and is provided with two eccentrically-disposed members, which impart movement in opposite directions to a means that controls the inlet and exhaust of the gases to and from the cylinders of the engine. In the form of our invention herein shown each of the plates 28 extends beyond one end of the cover 8 and is operatively connected with a disk-crank 41 on an operating shaft 42 by means of a crank-pin 43 and a plate or block 44, the latter being preferably rectangular and revolvably mounted on said crank-pin and being adapted to reciprocate in a transverse slot 45 in the end portion of said plate when the shaft 42 is rotated, causing, at the same time, longitudinally-reciprocatory motion of said plates. One of the crank-pins 43 is rigidly secured to the disk-crank 41, and bears an arm 46 to which the other crank-pin 43, is rigidly secured, said crank-pins being preferably located at substantially equal distances from the axis of rotation of the shaft 42 and being spaced apart from each other at substantially 47 degrees. The operating shaft 42 inclines slightly from the vertical and extends at substantially a right-angle to the plane of the top surface of the cylinder casing as best seen in Fig. 5, said operating shaft bearing a spiral gear-wheel 47, which meshes with a spiral pinion 48 on the crank-shaft 49, and being journaled in the brackets 50, which may be bolted or otherwise secured to the cylinder casing and the crank-casing. The gear-wheel 47 on the operating shaft 42 is preferably double the size of the pinion 48 on the crank-shaft, so that the operating shaft makes one revolution to two complete revolutions of the crank-shaft and thereby causes the crank-pins 43 to effect a complete reciprocation of each plate or valve member 28.

The ports 6 in the cylinders are comparatively narrow, as shown in Fig. 2, but the openings 30, 32, 34, 36, 38 and 40 in the bottom valve member are large enough so that they will establish communication between the ports 6 and the openings in the top valve member in proper sequence when the valve members reciprocate back and forth, the openings in the top valve member being smaller than the co-operating openings in the bottom valve member so that solid portions of the top member will lie between the inlet and exhaust passages and the openings in the bottom valve member, during certain positions of said members, and thus cut off the inlet and exhaust of the gases during certain positions of the bottom

valve member when the openings in same align with the ports in the cylinders. By forming the openings in the valve members in this way and providing the cylinders with 5 comparatively narrow ports, we prevent a large area of the valve members from being subjected to the excessive pressure in the cylinders during the compression strokes of the pistons and when the explosions occur. 10 Still another desirable feature of such a construction is that a single pair of openings in the valve members control both the inlet and exhaust of the gases to and from one of the cylinders. In the engine herein shown the 15 valve members are provided with two pairs of openings 29 and 30 and 39 and 40 that control the two end cylinders 1 and 4, and consequently, each valve member of a four-cylinder engine is provided with only six 20 openings instead of eight openings. In other words, each valve member is provided with separate and distinct inlet openings and exhaust openings for certain cylinders and with single openings for the remaining 25 cylinders through which the combustible gases and the exhaust gases pass.

In order to lubricate the plates 28, the upper surfaces of same and, also, the upper surface of the cylinder casing are provided 30 with relatively shallow transverse grooves 51, as best seen in Figs. 10, 11, and 12, to receive the lubricant which is forced through a pipe 52 or a plurality of such pipes into approximately vertical grooves 35 53 in the wall at the high side of the valve chamber 7, each pipe 52 being provided with a device 54 of any suitable construction for regulating the flow of the lubricant into the valve chamber and said pipe or 40 pipes 52 being communicatively connected with a centrifugal pump 55 by means of a pipe 56. The pump 55 is operatively mounted upon the shaft 42 preferably adjacent to the lower end of the latter and is 45 connected with the crank-casing by means of a pipe 57 so that same will pump oil from the crank-casing to supply the plates 28. Some of the grooves 51 in the plates 28 extend entirely across the upper faces of the 50 said plates to receive the lubricant from the grooves 53 while passing the latter, the other grooves 51 in said plates being preferably arranged to extend partly across same, terminating a short distance from 55 each side thereof as shown in Figs. 10 and 11. In like manner, some of the grooves 51 in the top of the cylinder casing are long and the others short, the long ones being arranged to extend from the bottoms of the 60 grooves 53 at the high side of the valve-chamber 7 to the drain ducts 58 in a flange 16 beyond the low side of the valve-chamber, and the short ones being arranged to extend partly across the bottom of said 65 valve-chamber, terminating a short distance

from each side thereof as depicted in Fig. 12. Pipes 59 which are connected with the ducts 58 conduct the lubricant back to the crank-casing.

A centrifugal water-circulating pump 60 is, also, operatively mounted upon the shaft 42 so as to be driven thereby, and has its outlet connected with the inlet pipe 24 of the water-jacket 22 and its inlet connected with a pipe 61 which is connected with the radiator (not shown), it being, of course, understood that the outlet pipe 25 of the water chamber 15 is, also, connected with the radiator.

A spiral gear-wheel 62 on the shaft 63 of a magneto electric generator 64 meshes with and receives its power from the spiral pinion 48; said shaft 63 being journaled in and said generator being supported by a bracket 65, which may be bolted or otherwise secured to the crank-casing. In this way, power is obtained from the pinion 48 to drive the generator 64 in addition to the operating shaft 42, it being, of course, understood that said generator will have the usual connections through a timing device (not shown in the drawings) with the spark plugs 26. If desired, the operating shaft 42 and parts operatively connected therewith, the pinion 48, and the gear 62 may be 90 enclosed in a housing 66 of any suitable construction.

In order to compensate for any wear upon the plates 28, a wear plate 67 or a plurality of such wear plates may be inlaid in the top 100 of the valve-chamber 7 and be held in engagement with the top surface of the upper plate 28 by means of a spring 68 or a plurality of such springs, said plate or plates 67 having openings 69 and 70, which register with the passages 13 and 14, respectively, in the cover 8, and bearing flanges 71 which project upwardly from the edges of the openings 69 and 70 to fit in rabbets 72 in the edges of the passages 13 and 14 as best seen 110 in Fig. 2.

The operation of the engine is as follows: Referring to Fig. 2, it will be seen that the plates or valve members 28 occupy such positions that they cut off communication between the ports 6 of the cylinders and the passages 13 and 14 in the cover 8, the pistons 5 within cylinders 1 and 4 being at the limit of their upward stroke and the pistons 5 within cylinders 2 and 4 being at the 115 limit of their downward stroke, and the opening 29 in the upper plate 28 and the opening 30 in the lower plate 28 being in position ready to establish communication between the port 6 of the cylinder 1 and the intake passage 13 above the latter, and the opening 35 in the upper plate 28 and the opening 36 in the lower plate 28 being in position ready to establish communication 120 between the port 6 of the cylinder 3 and the 125 port 6 of the cylinder 4. The piston 5 within cylinder 1 being at the limit of its downward stroke, the opening 29 in the upper plate 28 and the opening 30 in the lower plate 28 being in position ready to establish communication 130

exhaust passage 14 above the latter during the next movement of the plates 28. The crank-shaft 49 rotates in the direction of the arrow, Fig. 5, and thereby drives the operating shaft 42 counter-clockwise, Fig. 3, and, also, the shaft 63 of the magneto generator 64 through the medium of the spiral gearing. The rotation of the operating shaft 42 operates the pumps 55 and 66 and, also, the plates 28, as hereinabove described, and the shaft 63 operates the magneto generator. While the crank-shaft is rotated sufficiently to effect a charging or suction stroke of the piston 5 within the cylinder 1, a compression stroke of the piston 5 within the cylinder 2, an exhausting stroke of the piston 5 within the cylinder 3, and a power or firing stroke of the piston 5 within the cylinder 4, the lower plate 28 moves to the limit of its travel toward the left and then moves toward the right and the upper plate 28 moves to the limit of its travel toward the left, whereby the opening 30 in the lower plate 28 and the opening 29 in the upper plate 28 open and close communication between the port 6 of the cylinder 1 and the intake passage 13 above the latter, and the opening 36 in the lower plate 28 and the opening 35 in the upper plate 28 open and close communication between the port 6 of the cylinder 3 and the exhaust passage 14 above the latter. While the crank-shaft is rotated sufficiently to cause the piston 5 within the cylinder 1 to make a compression stroke, the piston 5 within the cylinder 2 to make a power or firing stroke, the piston 5 within the cylinder 3 to make a charging or suction stroke, and the piston 5 within the cylinder 4 to make an exhausting stroke, the lower plate 28 moves farther toward the right and the upper plate 28, also, moves toward the right thus causing the opening 38 in the lower plate 28 and the opening 27 in the upper plate 28 to open and close communication between the port 6 of the cylinder 3 and the intake passage 13 above the latter, and the opening 40 in the lower plate 28 and the opening 39 in the upper plate 28 to open and close communication between the port 6 of the cylinder 4 and the exhaust passage 14 above the latter. During the next rotary movement of the crank-shaft sufficient to effect a power or firing stroke of the piston 5 within the cylinder 1, an exhausting stroke of the piston 5 within the cylinder 2, a compression stroke of the piston 5 within the cylinder 3, and a charging or suction stroke of the piston 5 within the cylinder 4, the lower plate 28 moves to the limit of its travel toward the right and then toward the left, and the upper plate 28 moves to the limit of its travel toward the right, whereby the opening 40 in the lower plate 28 and the opening 39 in the upper plate 28 open and close communication be-

tween the port 6 of the cylinder 4 and the intake passage 13 above the latter, and the opening 34 in the lower plate 28 and the opening 33 in the upper plate 28 open and close communication between the port 6 of the cylinder 2 and the exhaust passage 14 above the latter. While the crank-shaft is rotated further to complete a cycle in each cylinder, the piston 5 within the cylinder 1 makes an exhausting stroke, the piston 5 within the cylinder 2 makes a charging or suction stroke, the piston 5 within the cylinder 3 makes a power or firing stroke, and the piston 5 within the cylinder 4 makes a compression stroke, the plates 28 move toward the left to their normal positions, whereby the opening 30 in the lower plate 28 and the opening 29 in the upper plate 28 open and close communication between the port 6 of the cylinder 1 and the exhaust passage 14 above the latter, and the opening 32 in the lower plate 28 and the opening 31 in the upper plate 28 open and close communication between the port 6 of the cylinder 2 and the intake passage 13 above the latter. In this way, communication between the ports 6 of the cylinders and their intake and exhaust passages 13 and 14 in the cover 8 is opened and closed in the proper sequence.

While it is preferable to have the plates 28 arranged to reciprocate in superimposed relation as hereinabove described, yet, it should be understood that, *mutatis mutandis*, said plates may be supported side by side on their edges and arranged to reciprocate in engagement with each other, as depicted in Fig. 13, to establish communication between the ports 6 of the cylinders and the passages 13 and 14 in proper sequence in the manner hereinabove described.

Various other changes in the details of construction and arrangement of parts may be made without departing from the nature and spirit of the present invention.

We claim:

1. A multi-cylinder internal combustion engine provided with reciprocating valve members arranged in sliding engagement with each other that control the inlet and exhaust of the gases to and from all of the cylinders, said members being provided with a pair of coöperating inlet openings and a pair of coöperating exhaust openings that control the inlet and exhaust of the gases to and from one of the cylinders and also being provided with a single pair of coöperating openings through which the gases are admitted to and exhausted from a different cylinder.

2. A multi-cylinder internal combustion engine, each cylinder of which is provided adjacent its upper end with a port, inlet and exhaust passage-ways arranged out of alinement with the ports in the cylinders.

and reciprocating valve members that govern the admission and exhaust of the gases to and from all of the cylinders in proper sequence, said valve members having coöperating openings, the openings in one member being of relatively greater area than the openings in the other member so as to establish direct communication between the ports and said inlet and exhaust passageways 10 when said valve members are in certain positions.

3. A four-cylinder internal combustion engine, each cylinder of which is provided at its upper end with a port, and two reciprocating valve members arranged in sliding engagement with each other and provided with six pairs of coöperating openings which are so proportioned and arranged that the gases will be admitted to and exhausted from the various cylinders in proper 20 sequence.

4. A multi-cylinder internal combustion engine provided with a valve chamber that is common to all of the cylinders, said valve chamber extending longitudinally of the engine and being transversely inclined, reciprocating valve members arranged in

said chamber for controlling the inlet and exhaust of the gases to and from all of the cylinders, and means for supplying a lubricating medium to the upper side or high side of said valve chamber. 30

5. A multi-cylinder internal combustion engine provided with a valve chamber that is common to all of the cylinders, said valve 35 chamber extending longitudinally of the engine and being transversely inclined, reciprocating valve members arranged in said chamber for controlling the inlet and exhaust of the gases to and from all of the cylinders, means for supplying a lubricating medium to the upper side or high side of said valve chamber, and means for conducting the lubricating medium away from the lower side of said valve chamber. 40 45

In testimony whereof we hereunto affix our signatures in the presence of two witnesses.

WALTER F. KOKEN.
ANTON J. PICHL.
